ELECTRICAL CONNECTOR ARRANGEMENTS

John H. Krehbiel, Downers Grove, Ill., assignor to Molex Products Co., Brookfield, Ill., a copartnership consisting of Fred A. Krehbiel, E. P. Krehbiel, L. E. Krehbiel, Marie Manatte, and said John H. Krehbiel

Filed Sept. 30, 1955, Ser. No. 537,827

8 Claims. (Cl. 339—176)

This invention relates to electrical connector arrangements and more particularly to plug and receptacle and components thereof.

An important object of the present invention is the provision of a device of the character described for making line connections, either with or without a panel mounting, for a plurality of circuits, including means for polarizing the plug and receptacle so that they can be united in only one way corresponding to the proper circuit arrangement.

Another object of the invention is the provision of identical parts for the contact members of both the plug and the receptacle which may be stamped out in progressive dies from metal stock, the thickness, temper and conductivity of which can be varied to accommodate different electrical load carrying capacities.

An important feature is that the contact members can be inserted in the molded insulating body from the rear thereof by a slight push which automatically, but removably, locks the contact members in place, without the need for any extraneous fastening means or dismantling and reassembling of the insulating members.

Another object is the provision of a spring contact member, for both the plug and receptacle, which is bent back upon itself in somewhat bow form with a flaring end thus providing both a firm mechanical connection and good electrical conductivity while facilitating application of the plug to the receptacle.

Still a further object is the provision of an improved clip which may be used either for holding the plug and receptacle together in a line assembly without a panel mounting or for holding one of the parts, such as the receptacle, to a panel and by which the receptacle may be readily mounted thereon or removed therefrom.

The foregoing and other objects and advantages will be apparent from the following description, taken together with the accompanying drawings, of an illustrative embodiment of the invention, and in which drawings—

Figure 1 is a side elevational view of the receptacle and plug in position to be united for electrical connection purposes;

Figure 2 is an enlarged fragmentary axial sectional view of the receptacle and plug assembly with the parts connected and with the receptacle clipped to a panel, broken lines showing how the clip may be used without the panel to clamp the receptacle and plug together as in a line connection;

Figure 3 is a perspective view of the receptacle without the contact members, the front or mating face of the receptacle being turned toward the observer;

Figure 4 shows a perspective view of the plug without the contact members, the rear face of the plug being turned toward the observer;

Figure 5 is a view on an enlarged scale, of one of the contact members ready to have a wire terminal inserted therein;

2

Figure 6 shows a plurality of the contact members, in chain or strip form as they may be supplied to the trade, and

5 Figure 7 shows a perspective view of the holding clip shown also in Figure 2;

Figure 8 shows a modified arrangement still following the present invention;

10 Figure 9 is a fragmentary perspective view, on the scale of Fig. 5, of one of the contact members shown in Fig. 10, modified as shown;

Figure 10 shows a further modified arrangement employing the contact member of Fig. 9;

Figure 11 shows another modified arrangement;

15 Figure 12 shows a partial view of a further modification of the contact member, on the scale of Figs. 5 and 9;

Figure 13 illustrates, on a reduced scale, use of the contact member of Fig. 12; and

20 Figure 14 shows a contact member having characteristics of the contact members of both Fig. 5 and Fig. 12.

Referring in detail to the illustrative construction shown in the drawings, the numeral 11 indicates a receptacle part and the numeral 12 a plug part of an electrical connector embodying the present invention.

25 The receptacle part 11 includes an insulating body 13 desirably molded of a dielectric initially plastic material to suitable form, for example, as shown in Fig. 3, and the plug part 12 similarly includes an insulating body 14, of similar material, molded to the form such as shown in Fig. 4.

30 The receptacle body 13 is provided with one or more and in this instance a plurality of through passageways 15, rectangular in cross-section, in each of which, as best seen in Fig. 2, is a transverse internal rib 16, the ribs 16 being on the same side, or, in this instance, the lower side of each of the passages and approximately centrally thereof. In addition to the passages 15 which are similarly aligned, the insulating body 13 desirably has one such passage 17 which is asymmetrically disposed in the sense that its longer direction runs vertically of the body 13 while the longer directions of the passages 15 extend horizontally. The passage 17 has a rib (not shown) similar to the rib 16 but disposed laterally thereof. The front or mating face 18 of the body 13 desirably has an embossment 19 centrally thereof

35 through which the passages 15 and the passage 17 open. The rear end 20 of the body 13 is reduced, in vertical dimension, with respect to the front end having the face 18, thus providing shoulders 21 at the upper end and 22 at the lower end of the body 13. The upper and lower surfaces 23 of the body 13 are here shown grooved as at 24 from front to rear and at its front end groove 24 is intersected by lateral notches 25, which together with the groove open into the front face 18 of the body 13 above and below, respectively, the embossment 19. Where the body is vertically enlarged at top and bottom as at 26, the latter has a peripheral cutout 27 opening into the groove 24 and notches 25. The shoulder 21 is also notched as at 28 on the rear face of the enlargement 26 on each side of the groove 24. The body 13 may have beaded edges 29 at its upper and lower ends of the reduced portion 20 margining the face of the body in which the groove 24 occurs.

40 The plug body 14 also has one or more and in this instance plurality of through passages 30 that are adapted to be oriented with the passages 15 of the receptacle, and another passage 31 that is adapted to be oriented with the passage 17 of the receptacle. The passages 30 have transverse internal ribs 32 similar to the ribs 16 of the body 13 but disposed, in the body 14, nearer the front ends of the passages. The ribs 32 are on the same side of the passages 30 and in this instance on the lower side thereof.

45 50 55 60 65 66 70 75 80 85 90 95

The passage 31 has a similar rib (not shown) disposed laterally therein.

The body 14 has a rear end 33 that is reduced from vertical dimension so as to provide a forward enlarged end 34 of the body 14 with a rearwardly-facing shoulder 35 at top and bottom of the body 14. The shoulders 35 are centrally notched as at 36.

As best seen in Fig. 5, each of the contact members 37 for both the receptacle and the plug, is formed from a sheet metal stamping, of copper for example, having a contact making end 38a and a wire receiving end 38b. The contact making end 38a has a flat portion 39 and a spring tongue portion 40 which is bent back upon the portion 39, first in a somewhat bowed portion 41 and then in an obliquely outwardly extending portion 42 constituting a free end for the spring tongue 40. The wire receiving end of the contact member 37 includes pairs of longitudinally related flanges 43 and 44, the pair of flanges 43 being longer than the pair of flanges 44 and being adapted to be bent around the insulating jacket 45 of a wire cable 46, which, as is well known in the art, is cut away from around the stranded wire 47 of the cable to leave an exposed wire terminal 48 that is passed between the pair of flanges 44, after which the flanges 44 are bent around the wire terminal 48 and clinched thereon. The flanges 44 are shown merging into upturned side edges 49 of the contact member 37 to serve further to retain the wire terminal 48 securely connected to the contact member. To provide a stop against which the wire terminal 48 may be brought into abutment to limit insertion of the cable 46 into the wire receiving end 38b of the contact member 37, the latter has a lug 50 struck from the plate 39 thereof and bent up normally thereto.

The contact members 37 are advantageously formed in strip gangs or chains as shown in Figure 6 connected by webs 51 from which they may be severed along lines 52 when desired for use, the webs 51 being cut off and discarded. The contact members may be stamped out in progressive dies from metallic sheet material, the stock thickness, temper and conductivity of which may be varied to suit different electrical load carrying capacities.

The clip 54 shown in Fig. 2 in two different uses, and also shown in perspective in Fig. 7, includes a base 55 running transversely of the clip and from which extends a ribbon-like strip 56 that is first in the plane of the base 55 and is then bent normally thereto as at 57 and then bent obliquely back on itself as at 58, the termination of the portion 58 being in the form of an ogee or Z-curve 59 that after providing a hump 60 has a free end 60a extending substantially in the same direction as the oblique portion 58.

Assembly of the parts is as follows:

After a cable 46 has had its wire terminal 48 secured to a contact member 37 as previously described, a contact member is pressed into the passages 15 and 17 of the receptacle body 13, and 30 and 31 of the plug body 14, from the rear end of the passage, the contact member being inserted in the passage so that the bowed spring tongue 40 thereof confronts the rib 16 or 32 as the case may be. By further firmly pressing the contact member into the passage the spring tongue 40 rides over the rib and the free end 42 of the spring tongue snaps into abutment with the rib. At this time, the lug 50 of the contact member is in position to abut the rib on the opposite face thereof, the contact member being thus inhibited from movement in either direction in the insulating body. If removal be desired, a suitable tool, such as a screw driver may be inserted in the passage alongside the spring tongue 40 to press free end 42 of the latter away from the rib and permit withdrawal of the contact member. In the case of the receptacle body 13, the length front to rear thereof and the location of the rib 16 in the passages is such that the spring tongue 40 of the terminal is completely enclosed by the body. In the case of the plug, the

body 14 thereof is shorter, front to rear, and the ribs in the passages thereof are located nearer the front or mating face 61 of the body 14 so that the contact members 37 carried by the plug part project outwardly from the latter a sufficient distance so that when the passages of the receptacle and the passages of the plug are oriented, the contact members of the plug may be pressed into the passages of the receptacle until the contact members of both are mutually engaged by a sliding frictional engagement as best seen in Fig. 2. In such engagement, the spring tongues 40 of each pair of engaging contact members are compressed to provide a firm mechanical securement and a good electrical connection, the spring tongues being placed under tension thereby but not sufficiently stressed to move the latter out of engagement with the internal ribs of the insulating body. Indeed, the abutment of the free end of the tongue with the rib serves to increase its resistance to compression by the mating contact, thereby enhancing the spring tension and thereby the mechanical securement and electrical connection.

While the passages of the receptacle and the passages of the plug are oriented for interengaging purposes, they are not aligned, since, as best seen in Fig. 2, to permit and to dictate overlapping of the interengaging contact members the passages of the plug are slightly offset vertically from the passages of the receptacle so that a bowed face of one contact member engages the plate face of the interengaging contact member. To facilitate and insure this relationship of the parts, the mating face 61 of the plug is recessed as at 61a to receive the embossment 19 of the mating face 18 of the receptacle by a slightly telescoping action.

It will be understood that by reason of the differently oriented passage 17 for the receptacle and the corresponding passage 31 of the plug, the plug and receptacle are polarized so that they can be interengaged in only one way, the mating faces of the receptacle and plug being images one or the other so to speak for this purpose. If desired the passages may be numbered as at 62 on the rear faces of the plug and receptacle, each number to indicate a circuit that may be completed by a pair of cables 46 the contact members of which are interengaged by the assembly as described. In this instance, eight such circuits are shown.

If it be desired to mount the receptacle body 13 on a panel, such as 63, for example, the panel may have an opening 64 therein of just sufficient size so that the rear reduced end 20 of the receptacle may be passed therethrough until the upper and lower shoulders 21 and 22 of the body 13 abut the panel. In this movement one of the clips 54 is laid in the groove 24 with the base 55 of the clip in the notches 25. As the body and clip are pushed together into the panel opening 64, the spring portion 58 of the clip is sprung against its inherent resilience until the edge of the opening 64 passes over the hump 60 of the clip. This may be done at top and bottom of the receptacle and thereupon the receptacle is firmly held to the panel until the spring portion 58 of the clip be depressed to permit the edge of the opening to pass in the opposite direction over the hump 60 to withdraw the clip and receptacle body.

Instead of mounting the receptacle on a panel it may be desired to make a line connection and in such case to clamp the receptacle and plug together. For that purpose, the clip 54 may be used in the manner shown in broken lines in Fig. 2, at which time the base 55 of the clip is laid in the notches 28 of the receptacle body with the remainder of the clip extending outwardly of the body toward the plug. When the receptacle and plug have been assembled to make the circuit connections the spring tongue 58 of the clip is then sprung over the shoulder 35 of the plug until the free end 60a of the clip snaps into the notch 36 in the shoulder 35, thus retaining the parts together until the clip is sprung against its inherent resilience to separate the plug and receptacle.

In some instances it may be desired to clamp the plug to the receptacle even when the latter is mounted on a panel and that may be done by the use of the clip in both of the ways just described, i.e., using two of the clips 54, one as shown in full lines in Fig. 2 and the other as shown in dotted lines, Fig. 2. Also it will be understood that the clips would be used at top and bottom of the connector.

In the modification shown in Fig. 8, the parts 65 and 65a correspond to the receptacle part 11 and the plug part 12 of the previous figures but in this modification may be substantially identical by reversing the facing direction of contact member 37 in the part 65a which corresponds to the plug part 12, that is by making the contact members 37 mutually engage on their bowed faces 41 as at 41a (Fig. 8). In this arrangement, the offset of the plug part with respect to the receptacle part shown in Fig. 2 is avoided and the passageway 15a of part 65 and 30a of part 65a are not only oriented but also aligned, as seen in Fig. 8.

Fig. 9 shows a modified form of contact member 66 which has a nub or pimple 67 extruded on its bowed portion 66a and another aligned pimple 68 extruded on its flat portion 66b, the use of this form of contact member being shown in Fig. 10 in which the pimple 67 on the bowed portion of the upper contact member snaps into the depression 69 formed by the pimple 68 on the flat portion of the lower contact member, as at 70, thus yieldingly locking the contact members together to prevent accidental separation.

Fig. 11 shows another modified arrangement in which the contact members 71 are bowed as at 72 on their portion corresponding to their flat portion 39 in the previous figures, the arc of the bow extending inwardly of the member so as to provide an extremity or bearing portion 72a on the contact member 71 of reduced area that is placed somewhat under tension, by the bowed effect 72, when the contact members are mutually engaged and engaged in the receptacle member as shown in Fig. 10, thus enhancing their interengagement.

Fig. 12 shows a further modification in which the contact member 73, corresponding otherwise to the contact member 37, is formed with a pair of additional side flanges 74 disposed forwardly of the wire receiving flanges 43 and 44 previously described and between the contact making end and the wire receiving end of the contact member. These additional side flanges 74, by being left upstanding, serve as a substitute lug in place of the tab or lug 50 of the previous figures. Enhanced strength for this lug formation thus provided is afforded by the flanges 74 which have their greater dimension in the direction of the force applied when the contact member is pushed into the receptacle or plug member, thus guarding against breakage or deformation of the lug when the internal rib 16 or 32 is engaged by the contact member to locate the latter in the dielectric body as previously described. This use of the flanges 74 as a stop lug limiting insertion of the contact member 73 into the insulating body 11 for example is illustrated in Fig. 13.

Figure 14 shows a contact member 75 having both the stop lug formation provided by the flanges 74 and also the stop lug formation provided by the tongue 50 of the previous figure, the latter being strengthened by the rib 50a formed therein. In the contact member 75 of Fig. 14, the stop lug provided by the struck-out tab 50 may limit insertion of the stranded (nor solid) wire entered into the wire receiving end of the contact member, while the flanges 74 act as a stop lug formation limiting insertion of the contact member into the passageway 15 by abutment of the flanges 74 with the rib 16, as previously described. To this end, the tab 50 is flush with the edges 74a of the flanges or wings 74.

Such changes may be made as fall within the scope of the appended claims without departing from the invention.

What is here claimed is:

1. In an electrical connector, a receptacle part and a plug part, slidably interengaging contact members carried by said parts respectively, said contact members being substantially identical for both parts and each comprising integrally a plate portion and a reverse bent portion and a wire-receiving portion, through passageways in the receptacle part and plug part receiving the contact members respectively from the rear ends of the parts, each passageway having a transverse internal rib intermediately therein, said reverse bent portion of each contact member including a spring tongue arranged to snap over said rib as the contact member is slid into the passageway to retain the contact member in position in the passageway, the contact members of the plug part projecting from the forward end of the plug part for entry into the passageways of the receptacle part.
2. The connector of claim 1 wherein each spring tongue is of bowed formation and terminates in an outwardly flaring free end for abutting said rib.
3. The structure of claim 1 wherein the plate portion of one contact member frictionally engages the spring tongue of its interengaging contact member.
4. The structure of claim 1 wherein the passageways in the respective parts are oriented but not aligned whereby the plate portion of one interengaging contact member frictionally engages the reverse bent portion of the other member.
5. A contact member for an electrical connector having a contact making end and a wire receiving end, said contact making end comprising a resilient metal stamping bent back upon itself at one end to provide a spring tongue, said spring tongue having an outwardly bowed portion and an outwardly flaring free end, said tongue being bowed for its entire length exclusive of said free end, said wire receiving end comprising a plurality of pairs of flanges of unequal length, a pair of longer length being arranged to be wrapped around the insulation of a wire cable and a pair of smaller length for being crimped over the bared wire terminal, and a lug struck out from the material of the contact member between the contact making end and the wire receiving end thereof, said lug extending in the same direction as said flanges.
6. The structure of claim 5 wherein the lug formation is struck out from the center of the plate part and has its broader face extending transversely to the plate part.
7. A contact member for an electrical connector having a contact making end including a plate portion and a resilient portion bent back upon itself to provide a bowed spring tongue, an extruded pimple formation in the inner face of the plate portion extending toward the spring tongue providing a complementary recess on the outer face of the plate portion, and another extruded pimple formation of like size on the spring tongue facing away from the plate portion, whereby a pimple formation on the spring tongue of the member may enter a recess in the plate portion of another like member.
8. A contact member for an electrical connector having a contact making end and a wire receiving end, said contact making end comprising a resilient metal stamping having a plate portion bent back upon itself at one end to provide a spring tongue, said plate portion being slightly bowed toward the tongue, said spring tongue having an outwardly bowed portion and an outwardly flaring free end, said tongue being bowed for its entire length exclusive of said free end, said wire receiving end comprising a plurality of pairs of flanges of unequal length, a pair of longer length being arranged to be wrapped around the insulation of a wire cable, and a pair of flanges of smaller length arranged for being crimped over the bared wire terminal, and a lug struck out from the material of the contact member between the contact

making end and the wire receiving end, said lug being extended in the same direction as said flanges.
